[57] CLAIM

The ornamental design for a diaper dispenser, as shown and described.

DESCRIPTION

FIG. 1 is a top, front, and left side perspective view of a diaper dispenser showing my new design;

FIG. 2 is a left side elevational view thereof, the right side being a mirror image of that shown;

FIG. 3 is a top plan view thereof;

FIG. 4 is a rear elevational view thereof;

FIG. 5 is a front elevational view thereof;

FIG. 6 is an exploded, top, front, and left side perspective view thereof;

FIG. 7 is an exploded rear elevational view thereof;

FIG. 8 is a top front, and left side perspective view of an alternate embodiment of a diaper dispenser showing my new design;

FIG. 9 is a left side elevational view thereof, the right side being a mirror image of that shown;

FIG. 10 is a rear elevational view thereof;

FIG. 11 is an exploded top, front, and left side perspective view thereof;

FIG. 12 is an exploded rear elevational view thereof;

FIG. 13 is bottom plan view of the upper portion thereof, with the lower portion removed for clarity of illustration; and,

FIG. 14 is a top plan view of the lower portion thereof, with the upper portion removed for clarity of illustration.

The bottom of all embodiments is plain and unornamented. The top plan view of the second and third embodiments of my new design is the same as shown in FIG. 3. The front elevational view of the third embodiment is the same as shown in FIG. 5.

FIG. 1**FIG. 2****FIG. 3****FIG. 4**

FIG. 5

FIG. 6**FIG. 7****FIG. 8**

FIG. 9

FIG. 10**FIG. 11****FIG. 12****FIG. 13****FIG. 14**
